UNITED STATES PATENT OFFICE.

LAWRENCE POETON, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

DESIGN FOR A TEMPLE.

51,654.

Specification for Design.

Patented Jan. 1, 1918.

Application filed September 13, 1917. Serial No. 191,294. Term of patent 14 years.

To all whom it may concern:

Be it known that I, LAWRENCE POETON, a citizen of the United States, residing at Southbridge, in the county of Worcester and State of Massachusetts, have invented a new and original ornamental Design for Temples, of which the following is a specification, reference being made to the accompanying drawings, forming a part thereof.

Figure I is a side elevation of a pair of temples illustrating my improved design, a pair of spectacles being illustrated in dotted lines, and

Fig. II is a side elevation of one of my improved temples.

Copies of this patent may be obtained for five cents each, by addressing the "Commissioner of Patents, Washington, D. C."

In the accompanying drawings the illustration shows an enlarged ear loop provided with a plurality of spaced circumferential grooves causing it to present the appearance of being divided into a series of short sections.

What I claim is—

The ornamental design for a temple as shown and described.

In testimony whereof, I affix my signature in the presence of two witnesses.

LAWRENCE POETON.
